LOOSE-LEAF BINDER

Clyde T. Cadwallader, Kenmore, N. Y., assignor
to Dorothy Cadwallader, Kenmore, N. Y.

Application May 18, 1944, Serial No. 536,136

3 Claims. (Cl. 129—17)

My invention relates to improvements in loose leaf binders in which the binding mechanism consists of a plurality of rings which pass through small holes arranged in a row along the binding margin of the sheets.

The objects of my invention are to provide a loose leaf binder in which the rings can be constructed of wire and the ring supporting structure can be constructed of flat material, and in which the rings of the binder can be opened or closed for the purpose of inserting or withdrawing sheets without manipulating the rings individually.

A further object of my invention is to provide a binder in which each ring consists of two interacting wire loops which reinforce each other and give additional stability and rigidity to the ring binder assembly.

In the drawing:

Figure 1 is a fragmentary top view of a notebook in an opened position in which the covers are not shown;

Figure 2 is an elevation of the binder with the covers and sheets removed;

Figure 3 is a vertical section taken on the line 3—3 of Figure 1;

Figure 4 is a view in perspective of one of the wire loops;

Figure 5 is a vertical section taken on the line 3—3 of Figure 1, corresponding with Figure 3, with the rings in an opened position.

The rings of the binder are composed of two inwardly curved wire loops 1—1 which engage each other when the loops are in a closed position by the interaction of their overlapping and underlapping end surfaces, as shown in Figure 3. When in such closed position each pair of loops describes an arc of approximately 240 degrees of a circle slightly flattened at the top.

At their other ends loops 1—1 are each provided with short feet, 8 and 9 respectively. Feet 8 and 9 are disposed in opposite directions, foot 8 being pointed inwardly relative to the arc generally described by loop 1 and foot 9 being pointed outwardly thereof, as shown in Figure 4.

Two loop supporting frame plates 10—10 are provided with a series of pairs of small holes 11 adapted to receive the prongs of loops 1—1. Loop supporting frame plates 10—10 are attached to back plates 12—12 by rivets 13, or by any other suitable means, so that feet 8 and 9 of loops 1—1 are in contact with loop supporting frame plates 10—10 and back plates 12—12. The effect of feet 8 and 9 being wedged in between loop supporting frame plates 10—10 and back

plates 12—12 is to support loops 1—1 in upright and rigid positions relative to their respective back plates.

Back plates 12—12 are hinged together at their inner edges by a fabric hinge 14 and are hinged at their outer edges to covers 15—15 by the same means, the fabric hinge 14 being adhesively attached to back plates 12—12 and covers 15—15.

Between loop supporting frame plates 10—10 and back plates 12—12 at each end, and in frictional contact therewith, are stiffener plates 16—16, each of which is pivotally mounted on a pin 17 and intercepted by a stop 18. When stiffener plates 16—16 are pulled out of engagement with loop supporting frame plates 10—10 and back plates 12—12 the back of the binder can be broken inwardly, as is shown in Figure 5, so as to move into an opened position loops 1—1, permitting the insertion or withdrawal of sheets 19. Sheets 19 are provided with holes 20 into which either row of loops 1—1 are inserted.

Although Figures 1, 2 and 3 show the loop supporting frame plates 10—10 and back plates 12—12 to be of the same dimensions, this need not necessarily be so. If covers 15—15 are of stiff material it may be of advantage for them to converge as they approach the edges opposite the binding edge, as is a well known feature in notebooks of this type. This can readily be accomplished by making back plates 12—12 slightly wider than loop supporting frame plates 10—10, thus causing them to project slightly beyond the lines of the loop supporting frame plates at their outer edges. Such an arrangement is shown in Figure 5.

The advantages of my invention are that it provides a binder whose pages and covers lie flat on the supporting surface, that it provides a series of rings, each of which is in contact with 40 the pages when they are being turned at four points instead of one, thus dividing the strain at the holes and counteracting the tendency of the pages to tear loose, that it permits an indefinite increase in the number of rings to be used, and that it reduces the thickness of the binder.

It will be observed that material other than wire can be used without departing from the spirit of my invention. For instance, each of the rings could be composed of two overlapping 50 prongs of flat or of arcuate cross section, each prong provided at its lower end with a pair of legs bent at their respective ends to form two feet, one foot pointed inwardly of the arc generally described by the prong, and the other pointed outwardly thereof.

I claim:

1. In a ring binding construction for a stack of sheets, a plurality of pairs of prongs curved inwardly to form rings, each ring describing an arc of approximately 240 degrees of a circle slightly flattened at the top, the prongs overlapping at their engaging ends to permit them to interlock detachably, each prong provided at its lower end with a pair of feet, one of which is pointed inwardly of the arc generally described by the prong and the other pointed outwardly thereof, a pair of frame plates provided with spaced pairs of holes into which the feet are inserted, a pair of back plates attached to the frame plates and retaining the feet between one back plate and its corresponding frame plate, the back plates being hingeably attached to each other at their inner edges so as to permit the back of the binder to be broken inwardly and longitudinally, a pair of stiffener plates one at each end of the binder pivotally mounted between one back plate and its corresponding frame plate and in frictional contact with the other frame plate and back plate at their ends, and adapted to hold the prongs in overlapping engagement when the stiffener plates are in engagement with both frame plates and with both back plates, and releasable to permit the loops to be drawn apart when the stiffener plates are taken out of such engagement and the back of the binder is broken inwardly and the outer or lower surfaces of the back plates are moved into contiguity with each other on their connecting hinge.

2. In a ring binding construction for a stack of sheets, a plurality of pairs of wire loops curved inwardly to form rings, each ring describing an arc of approximately 240 degrees of a circle slightly flattened at the top, the loops overlapping at their engaging ends to permit them to interlock detachably, each loop provided at its lower end with a pair of feet, one of which is pointed inwardly of the arc generally described by the loop and the other pointed outwardly thereof, a pair of frame plates provided with pairs of spaced holes into which the feet are inserted, a pair of back plates attached to the frame plates and retaining the feet between one back plate and its corresponding frame plate, the back plates being hingeably attached to each other at their inner edges so as to permit the back of the

binder to be broken inwardly and longitudinally, a pair of stiffener plates one at each end of the binder pivotally mounted between one frame plate and its corresponding back plate and in frictional contact with the other frame plate and back plate at their ends, and adapted to hold the loops in overlapping engagement when the stiffener plates are in engagement with both frame plates and with both back plates, and releasable to permit the loops to be drawn apart when the stiffener plates are taken out of such engagement and the back of the binder is broken inwardly on the hinge between the back plates to permit the insertion or withdrawal of sheets provided with holes.

3. In a ring binding construction for a stack of sheets, a plurality of pairs of wire loops curved inwardly to form rings, each ring describing an arc of approximately 240 degrees of a circle slightly flattened at the top, the loops overlapping at their engaging ends to permit them to interlock detachably, each loop provided at its lower end with a pair of feet, one of which is pointed inwardly of the arc generally described by the loop, and the other pointed outwardly thereof, a pair of frame plates provided with pairs of spaced holes into which the feet are inserted, a pair of back plates attached to the frame plates and retaining the feet between one back plate and its corresponding frame plate, the back plates being hingeably attached to each other at their inner edges, a pair of covers hingeably attached to the back plates at their outer edges by a flexible covering adhesively attached to the back plates and covers at their outer surfaces and adapted to permit movement of the back plates to a position where they are contiguous at their outer surfaces and the loops are drawn apart, permitting the insertion or withdrawal of sheets, a pair of stiffener plates one at each end of the binder pivotally mounted between one frame plate and its corresponding back plate and in frictional contact with the other frame plate and back plate at their ends, and adapted to hold the loops in overlapping engagement when the stiffener plates are in engagement with both frame plates and with both back plates, and releasable to permit the loops to be drawn apart when the stiffener plates are taken out of such engagement.

50 CLYDE T. CADWALLADER.
